CLAIM

The ornamental design for a archery bow cover, as shown and described.

DESCRIPTION

FIG. 1 is a front side elevation view of my new archery bow cover showing the new design;

FIG. 2 is a rear side elevation view thereof;

FIG. 3 is a side elevation view taken generally from the left side of FIG. 1 and looking towards the right;

FIG. 4 is a side elevation view taken generally from the right side of FIG. 1 and looking towards the left;

FIG. 5 is a end view of FIG. 1 taken generally from above the top of FIG. 1 and looking downwards towards the top end; and,

FIG. 6 is a end view of FIG. 1 taken generally from below the bottom of FIG. 1 and looking upwards toward the bottom end.

The broken phantom line showing of a side elevational view of a archery bow in FIG. 1, is for illustrative purposes only and forms no part of the claimed design.
